UNITED STATES PATENT OFFICE.

CHARLES O. GROENER, OF CANTON, OHIO, ASSIGNOR OF ONE-HALF TO GRANT TOTTEN, OF CANTON, OHIO.

DISPENSING CARTON.

Application filed May 4, 1927. Serial No. 188,667.

The invention relates to dispensing cartons or boxes, and more particularly to a box provided with a pouring spout.

Boxes of this kind are particularly adapted for holding any dry, powdered or granular substance, such as cereal foods, spices, soap powders or chips, and the like, which may be dispensed in small quantities, from time to time.

10 The object of the invention is to provide a carton or box having a pouring spout formed from one corner portion of the box and arranged to be easily moved into operative position, when it is desired to dispense a portion of the contents of the box, and to be replaced in closed position, to entirely enclose the contents when the box is not in use.

An embodiment of the invention is illustrated in the accompanying drawing, in which 20 Figure 1 is a perspective view of the improved box, showing the pouring spout in closed position;

Fig. 2, a similar view, showing the pouring spout in the open, or operative position;

25 Fig. 3, a fragmentary side elevation of the box, showing the pouring spout in open position;

Fig. 4, a fragmentary top plan view of the box, in the same position as in Fig. 3; and

30 Fig. 5, a detail sectional view of the box, showing the pouring spout in closed position.

Similar numerals refer to similar parts throughout the drawing.

The box or carton 1, may be made of pasteboard or the like, constructed in any usual and well known manner, and may be of any size, shape or proportion adapted to the material to be contained therein.

One face of the box, as indicated at 2, in the 40 drawing, is arranged to have the pouring spout formed integrally therewith. As best shown in Fig. 2, the triangular side 3 of this spout is formed from the corner of the face 2 of the box.

45 The wall or face 2 of the box has the angular flange portion 4 pasted or otherwise attached to the adjacent wall 5 of the box, this flange 4 terminating at the lower angle of the spout as shown at 7.

50 The spout has the inturned angular flap 8 formed integrally with the triangular portion 3 thereof and provided with a V-shaped notch 9 in its inner straight free edge.

55 The upper edge of the wall 2 of the box is provided with an inturned angular flange 10

adapted to be pasted or otherwise connected to the top wall 12 of the box.

When it is desired to use the spout to dispense the contents of the box it is only necessary to pull the spout out into the position shown in Figs. 2, 3 and 4, engaging the V-shaped notch 9 with the edge of the side wall 5, the tab 13, beyond this notch being hooked over the outer side of the wall 5.

In order to prevent any of the contents of the box or carton from being accidentally spilled in shipping, the entire box may be covered with a thin paper covering 14 pasted or otherwise secured thereto. In order to use the spout to dispense the contents of the box, it is only necessary to cut through this thin paper wrapping along the dotted lines indicated at 15 in Fig. 1, when the spout may be operated as above described.

Although the pouring spout is shown in one upper corner of the box, it should be understood that this spout may be placed in any desired location upon any part of the box.

I claim:

1. A dispensing carton having a portion 80 of one wall separable, an angular flap extending inward into the carton from the separable portion to form a pouring spout, the inner free edge of said flap being straight and there being a V-shaped notch in the inner straight 85 edge forming a tab beyond the V-shaped notch, and the flap being adapted for removal from the interior of the carton so that the tab may be entirely removed from the carton and positioned over the adjacent wall of the carton by engaging the adjacent wall by the V-shaped notch.

2. A dispensing carton having a corner portion of one wall separable, an angular flap extending inward into the carton from the separable portion to form a pouring spout, the inner free edge of said flap being straight and there being a V-shaped notch in the inner straight edge forming a tab beyond the V-shaped notch, and the flap being adapted for removal from the interior of the carton so that the tab may be entirely removed from the carton and positioned over the adjacent wall of the carton by engaging the adjacent wall by the V-shaped notch.

3. A dispensing carton having a triangular portion of one wall separable, an angular flap extending inward into the carton from the separable portion to form a pouring spout, the inner free edge of said flap being

straight and there being a V-shaped notch in the inner straight edge forming a tab beyond the V-shaped notch, and the flap being adapted for removal from the interior of the carton so that the tab may be entirely removed from the carton and positioned over the adjacent wall of the carton by engaging the adjacent wall by the V-shaped notch.

4. A dispensing carton having a triangular corner portion of one wall separable, an angular flap extending inward into the carton from the separable portion to form a pouring spout, the inner free edge of said

flap being straight and there being a V-shaped notch in the inner straight edge ¹⁵ forming a tab beyond the V-shaped notch, and the flap being adapted for removal from the interior of the carton so that the tab may be entirely removed from the carton and positioned over the adjacent wall of the carton ²⁰ by engaging the adjacent wall by the V-shaped notch.

In testimony that I claim the above, I have hereunto subscribed my name.

CHARLES O. GRONER.
